UNITED STATES PATENT OFFICE.

SAMUEL McGAHEY, OF EASTON, PENNSYLVANIA.

TOY.

Application filed January 22, 1926. Serial No. 83,090.

This invention relates to aerial toys, and contemplates the provision of a frame-like member which is adapted to be held in one hand, and designed to support a projectile, the latter being projected into the air incident to the unwinding of a cord therefrom, the invention residing in the construction, combination, and arrangement of parts as claimed.

10 In the drawing forming part of this application, like numerals of reference indicate similar parts in the several views, and wherein:—

Figure 1 is a side elevation of the toy constructed in accordance with the invention.

Figure 2 is a fragmentary detail view of the frame-like member.

Figure 3 is a sectional view through the propeller of the projectile.

20 Referring to the drawing in detail, 10 indicates a substantially U-shaped frame member which terminates to provide eyes 11 through which the stem 12 of the projectile passes. The stem supports a propeller 13 which is bevelled as at 14. Supported by one of the parallel portions of the frame 10 is a substantially L-shaped piece of metal or other suitable material 15, which is arranged immediately beneath the adjacent eye 11, 25 and this material supports the stem of the projectile. As shown in Figures 1 and 2 this piece of material is relatively broad and has one end folded or bent upon itself to provide a sleeve-like portion adapted to surround the adjacent limb of the U-shaped frame, thus providing a construction whereby this member can be easily replaced should it become broken, bent or otherwise impaired beyond use. The stem is provided with a

bore or opening to receive one end of a 40 string 17 which is adapted to be wound about the stem in a manner illustrated in Figure 1. The cord or string has associated therewith a finger receiving ring 18. In using the toy, the frame 10 is held by the 45 left hand, and the string forcibly unwound from the stem of the projectile, thereby rotating the latter in a manner which causes the projectile to shoot upwardly an appreciable distance into the air. The toy is very 50 simple in construction, and can be manufactured at a very nominal cost.

While it is believed that from the foregoing description, the nature and advantages of the invention will be readily apparent, I desire to have it understood that I do not limit myself to what is herein shown and described, and that such changes may be resorted to when desired as fall within the scope of what is claimed. 60

What I claim is:—

A toy of the character described comprising a frame having parallel limbs terminating to provide aligned eyes, a projectile including a stem passed through said eyes, a 65 propeller carried by the upper end of the stem, a substantially L-shaped member formed from a single piece of material, and folded upon itself at one end to provide a sleeve adapted to embrace the adjacent limb 70 of the frame, whereby said member is supported beneath the limb and used as a rest for the lower end of the stem, and a flexible element adapted to be wound about the stem and unwound therefrom for the purpose 75 specified.

In testimony whereof I affix my signature.

SAMUEL McGAHEY.
